UNITED STATES PATENT OFFICE.

JOHN R. THOMAS, OF CINCINNATI, OHIO, ASSIGNOR TO J. A. FAY & EGAN COMPANY, OF CINCINNATI, OHIO, A CORPORATION OF WEST VIRGINIA.

GAINING-MACHINE.

No. 880,177.

Specification of Letters Patent.

Patented Feb. 25, 1908.

Application filed August 24, 1907. Serial No. 389,936.

To all whom it may concern:

Be it known that I, JOHN R. THOMAS, a citizen of the United States, residing at Cincinnati, in the county of Hamilton and State of Ohio, have invented certain new and useful Improvements in Gaining-Machines, of which the following is a specification.

It is the object of my invention to provide a new and useful gaining machine such as is employed for instance in providing a timber with gains or grooves cross-wise of the timber, and the invention consists in new and useful instrumentalities for initiating, reversing and stopping the stroke of the gaining-head, and in various other instrumentalities which will be more readily understood from the following description and claims, and from the drawings, in which latter:

Figure 1 represents a side elevation of my improved device. Fig. 2 is a plan view of the same, with the table partly broken away. Fig. 3 is a front elevation of the same. Fig. 4 is a rear elevation of the same. Fig. 5 is an enlarged detail in side elevation of the tripping mechanism. Fig. 6 is an end elevation of the same. Fig. 7 is a plan view of the same, shown in connection with the tappets. Fig. 8 is a plan view of the guide for the trip. Fig. 9 is a vertical section of the same on the line $x-x$ of Fig. 8; and, Fig. 10 is a sectional detail on the line y of Fig. 1 showing the manner of mounting the driving bevel-friction wheels.

1 represents a column which supports a saddle 2 for the gaining-head reciprocating in slide-ways 3 on the column. 4 is a slide slidable in guide-ways 5 at the front of the saddle and carrying the bearings 6 for a gaining-head shaft 7, to which a suitable gaining-head 8 is adapted to be secured. The gaining-head is adapted to be rotated by a belt passing from above under a pulley 9 on the saddle, thence around a pulley 10 on the shaft 7, thence backwardly, under a pulley 11 on the saddle and upwardly from the latter, the belt being operated by suitable driving pulleys from above, suitable take-up mechanism being provided to take up the slack of the belt which may be occasioned by the change of positions of the shaft 7. Suitable limiting plugs 15 are adjustable in slots

16 of the slide and are adapted to strike a rail 17 of the saddle for limiting the up and down movement of the slide, these plugs 55 being releasable in usual manner.

There is a rack 21 at the bottom of the saddle with which a gear 22 engages, the gear being on a shaft 23 journaled in bearings 24 of the frame. A pinion 25 meshes with the gear 22 and is on a shaft 26 journaled in bearings 27 of the frame, this shaft also having a worm-wheel 28 thereon which is meshed by a worm 29 on a shaft 30 journaled in bearings 31 in the frame. The shaft 60 30 also carries a beveled-friction wheel 32 with which beveled-friction wheels 33 34 are adapted to selectively engage for turning the shaft 30 in reverse directions, the bevel-friction wheels 33 34 being on a sleeve 35 70 having spline-connection 36 with a drive-shaft 37 journaled in bearing 38 of the frame and provided with suitable driving connection as for instance pulleys 39. The bevel-friction wheels 33 34 are spaced apart sufficiently to permit the same to be positioned out of contact with the bevel-friction wheel 32 and to permit either bevel-friction wheel 33 or 34 to be brought into contact with the bevel-friction wheel 32 by the end-wise 75 shifting of the sleeve 35. This end-wise shifting is accomplished by means of a block 41 taking about the sleeve and having a slot 42, with the walls of which the end of a shifter-finger 44 is adapted to engage, the shifter-finger being on a rock-shaft 45 having a manipulating arm 46 secured thereto, the arms 44 46 and the rock-shaft 45 thus preferably forming a bell-crank lever for the manipulation of the bevel-friction engagement. 90

There is a moving agency provided for normally causing one of the sliding bevel-friction wheels to engage the driven bevel-friction wheel as well as means for normally holding the sliding bevel-friction wheels out 95 of contact with the driven friction wheel, this latter position causing the saddle to remain in a position of rest. Thus a rod 51 depends from the arm 46 through a lug 52 on the frame and at its bottom carries a collar 53 positioned by means of a set-nut 54 and a jam-nut 55. A spring 56 takes about the rod between the lug and collar for normally pressing the shifter-arm 46 down-

wardly, thus normally tending to cause engagement between the friction-wheels 33 32. A rod 59 extends upwardly from the shifter-arm 46, the rods 59 and 51 being shown articulated with the shifter-arm on a bolt 60. An operating lever 61 is articulated with the rod 59 at 62 and is pivoted on a bolt 63 to the frame and at its outer end has a handle 64 for manual manipulation, the object of the 10 operating lever being to raise the outer end of the shifter-arm 46 for bringing the friction-wheel 34 into engagement with the friction-wheel 32.

To the rod 59 a bar 66 is pivoted at 67. 15 A link 68 is articulated with the bar 66 at 69 and with a shifting-lever 70 at 71, the shifting-lever 70 being shown as a bell-crank lever pivoted to the operating lever at 72 adjacent to the handle 64. The link is preferably 20 provided with a turn-buckle 73. The bar 66 is adapted to slide in a slot 76 of a bearing 77. The bar 66 is provided with a shoulder 78 adapted to engage the bearing when the bar is raised for retaining the bar in 25 raised position. The shoulder 78 preferably engages a hardened bearing-plate 80 at the top of the bearing, which thereby forms a mating shoulder for the shoulder 78, and forms a rest for the bar 66. There is a spring 30 81 in a pocket 82 of the bearing 77 for normally urging the shoulder 78 toward the stop or rest 80. This spring 81 acts upon the bar 66 for normally causing engagement between the shoulders 78 80 when the outer end of the 35 operating lever 61 is depressed for raising the rod 59 and thereby raising the outer end of the shifter-arm 46 for causing engagement between the friction-wheel 34 and the friction-wheel 32. I preferably provide an adjustment for the bearing 77, by providing the same with slots 83 through which bolts 84 are received into the column, and by providing the column with lugs 85 into which bolts 86 are threaded for engaging the bearing.

40 45 The saddle is provided with a pair of tappets 87 88 the tappet 87 being adapted to shift the bar 66 laterally in the forward movement of the saddle for disengaging the shoulders 78 80, and the tappet 88 being provided with a shelf 89 upon which an anti-friction roll 90 at the upper end of the bar 66 is adapted to ride, the upper face of the shelf being provided with a downward slope 91 at its rear end for readily taking under the anti-friction roll 90 in the rearward movement of the saddle for raising the bar 66, and thereby partially raising the outer end of the shifter-arm 46 for positioning the friction-wheels 33 34 in neutral position with relation to the 50 55 60 friction-wheel 32 for causing the saddle to be at rest. The tappet 87 is provided with a striking-lug 92, preferably receding downwardly and rearwardly, this lug striking the roller for moving the bar. The tappets 87

88 are adjustably positioned lengthwise of the saddle along a guide-way 93, as by means of T-bolts 94 whose heads are received in an undercut slot of the guide-way and have nuts 95 at their outer ends, for determining the length of stroke of the saddle. 70

It will be understood that the normal position of the frictions is a neutral position, with the friction-wheels 33 34 positioned intermediate of their limits of movement and out of contact with the friction-wheel 32. This 75 position is attained when the roller 90, or other contact part which may be used therefor, rests on the shelf 89. If it is desired to initiate movement of the saddle, the handle 64 is pressed downwardly, thus raising the 80 rod 59 and causing the shoulder 78 to be received upon the rest 80, thus causing engagement between the friction-wheels 34 and 32 and causing forward movement of the saddle. When this forward movement has progressed 85 sufficiently for causing the lug 92 to strike the roller 90, the shoulder 78 will be forced off of the rest 80 and the bar caused to drop, the tension of the spring 56 thereby forcing engagement between the friction-wheels 33 90 and 32 and causing the reverse or rearward movement of the saddle until the shelf 89 passes under the roll or contact part 90 for raising the bar 66 and the rod 59 and causing the friction-wheels 33 34 to be shifted into 95 neutral position with relation to the friction-wheel 32 and thereby causing cessation of movement of the saddle.

Up and down movement of the gaining-head may be had by manipulation of the 100 levers 101 which are pivoted at 102 on uprights 103 secured to the saddle and are connected at their front by a cross-bar 104 serving as a handle and at their rear by a cross-bar 105 on which suitable weights 106 may 105 be secured for normally holding the slide in upward position. At each side of the slide a rod 107 is pivoted at 108 to which the levers 101 may be clamped at desirable points by swivel clamps 109. 110

The timber, which is shown at 111, is adapted to be clamped upon a table 112 to which lengthwise movement may be imparted in suitable manner for positioning the timber or other work being operated on at 115 suitable points with relation to the cutting-head of the machine. The table is provided with tracks 113 supported on wheels 114. The table also has a rack 115 with which a gear 116 meshes, the gear being driven from a pinion 117 on a shaft 118 which also carries a gear 119 meshed by a pinion 120 on a shaft 121 carrying a hand-wheel 122. 123 124 are tappets adjustable lengthwise of a rod 125 on the table. 126 is a stop-block normally 125 out of range of the tappets. It slides in a bearing 127 and has connection with a foot-lever 128 by means of which it is adapted to

be raised into range of the tappets for forming a definite stop for the lengthwise travel of the carriage for positioning the timber lengthwise with relation to the cutter head on the 5 saddle 2.

Having fully described my invention what I claim as new and desire to secure by Letters Patent is:

1. In a gaining machine, the combination, 10 with a cutter-head saddle and means for driving the same, of means for affecting the direction of movement of said cutter-head saddle comprising an operating lever, a link articulated therewith and having connection with 15 said driving means, a bar articulated with said link, and a stop for said bar, said bar having connection with said operating lever for permitting release of the same from said stop, substantially as described.

20 2. In a gaining machine, the combination, with a reciprocating cutter-head saddle and means for driving the same, said driving means comprising a shiftable member, of an operating lever having a handle, a link articulated therewith and having connection with said shiftable member, a rod having connection with said shiftable member and provided with a stop, and a second link articulated with said rod and with said operating 25 lever adjacent the handle thereof, substantially as described.

3. In a gaining machine, the combination, 30 with a reciprocating cutter-head saddle and means for driving the same, said driving means comprising a shiftable member, of an operating lever having a handle, a link articulated therewith and having connection with said shiftable member, a rod having connection with said shiftable member and provided with a stop, a second link articulated with said rod and with said operating 35 lever adjacent the handle thereof, and a spring for normally urging said shiftable member in a given direction, and constructed and arranged for shifting said shiftable member in the opposite direction by the manipulation of said operating lever, substantially as described.

4. In a gaining machine, the combination, 40 with a frame, a reciprocating cutter-head saddle thereon, and means for driving the latter, said driving means comprising a shiftable member, of an operating lever having a handle, a link articulated therewith and having connection with said shiftable member, a rod having connection with said shiftable member and provided with a shoulder, said frame provided with a shoulder with which said first-named shoulder is arranged to 45 make engagement, a spring for normally urging said shoulders into engagement, and a second link articulated with said rod and with said operating lever adjacent the handle thereof, substantially as described.

5. In a gaining machine, the combination, 50 with a frame, a reciprocating cutter-head saddle thereon, and means for driving the latter, said driving means comprising a shiftable member, of an operating lever having a handle, a link articulated therewith and having connection with said shiftable member, a rod having connection with said shiftable member and provided with a shoulder, said frame provided with a shoulder with which said first-named shoulder is arranged to 55 make engagement, means for adjusting the relative position between said shoulders, a spring for normally urging said shoulders into engagement, and a second link articulated with said rod and with said operating lever adjacent the handle thereof, substantially as described.

6. In a gaining machine, the combination, 60 with a frame, a reciprocating cutter-head saddle thereon, and means for driving the latter, said driving means comprising a shiftable member, of an operating lever having a handle, a link articulated therewith and having connection with said shiftable member, a rod having connection with said shiftable member and provided with a shoulder, said frame provided with a shoulder with which said first-named shoulder is arranged to 65 make engagement, a spring for normally urging said shoulders into engagement, a second link articulated with said rod and with said operating lever adjacent the handle thereof, a depending rod having connection with said shiftable member, and a spring for 70 said depending rod normally urging said shiftable member in a given direction, and constructed and arranged whereby said shiftable member is urged in the opposite direction by manipulation of said operating lever, substantially as described.

7. In a gaining machine, the combination, 75 with a frame and reciprocating cutter-head saddle therefor, of means for driving said saddle comprising a shiftable transmitter, a lever for shifting the latter, an operating lever pivoted with relation to said frame, a link connecting said levers, a bar pivoted to said link, said bar having a stop, a rest on said frame for said stop, a tappet on said saddle for relatively disengaging said stop 80 and rest, and a raising tappet on said saddle for said bar, substantially as described.

8. In a gaining machine, the combination, 85 with a frame and reciprocating cutter-head saddle therefor, of friction driving means for 90 said saddle comprising a shiftable member, a lever having connection therewith, a spring therefor, an operating lever, a link between the latter and said first-named lever, a bar articulated with said link having a stop 95 thereon, a rest on said frame for said stop adapted to engage upon raising said link by said operating lever, means having connec-

tion with said operating lever and bar for manually disengaging said stop and rest, a tappet on said saddle for causing disengagement between said stop and rest, and a tappet on said saddle for causing neutral positioning for said frictions, substantially as described.

In testimony whereof, I have subscribed my name hereto in the presence of two subscribing witnesses.

JOHN R. THOMAS.
